ELECTRICAL WIRING
Richard H. Peterson, 10108 Harnew Road E.,
Oaklawn, Ill. 60453
Filed Mar. 30, 1965, Ser. No. 443,796
18 Claims. (Cl. 317—119)

This is a continuation-in-part of application Ser. No. 122,374, filed June 26, 1961, now Patent No. 3,197,541.

My invention relates to complicated electrical wiring systems of the type employed in the wiring for electronic musical instruments, and analogous wiring.

It includes among its objects and advantages material mechanical improvements over the construction disclosed in my earlier application. In the structure disclosed in said earlier application the printed conductor extended the entire width of the panel, and for the most perfect circuitry at the low voltages employed in transistorized circuitry such strips are customarily gold plated. A material shortening of this conductor is achieved according to the present invention.

The gripping of the next panel was between metal jaws in the earlier applications, with substantially a line contact area for one of the jaws. When such jaws are made heavy enough to carry the mechanical loads involved without deleterious flexure, they become quite rigid, and the clamped panel is likely to fulcrum on its electrical line contact with one jaw and permit shifting movement that is not noticeable when handling the apparatus but that may shift the electrical contact and introduce appreciable extraneous noises after a short period of use.

Because of the strength and stiffness of such jaws, very little distortion in repeated assembly and disassembly is necessary to cause one or two out of some sixty such jaws to be a little bit loose when all the others are getting satisfactory electrical contact and the location of such a circuit defect always involves a service call and annoyance to the user.

According to the invention the insulating panels themselves are arranged for panel-to-panel contact over a large area, under relatively small mechanical loads expressed in pounds per square inch of panel surface, and the electrical contact points pressing the panels together function with smaller total loads and much larger loads per unit of contact area and are made resilient through a large range of movement, so that with the inserted panel in correct position, the total pressure of all the electrical contact points will give firm and durable mechanical assembly of all the parts and hold them against any relative movement by the combined action of the pressure of the points and the friction between the panels. In one embodiment an electrical contact between one flat surface and a curved wire secures the desired small area, light total load, and large load per unit area.

The yielding of such electrical contact points at the time the panel is inserted can be from 5 to 15 times as much, measured in actual displacement, as in the previous construction, and a discrepancy of 15 thousandths of an inch or so between the points of the various individual contact members when undistorted still leaves the effective electrical contact pressure on every contact area within the range of suitable contact pressures for electrical transmission at low voltage, with a wide margin of safety.

Many economies in the processes of production and assembly are also available. These and other advantages will become apparent as the description proceeds.

In the accompanying drawings:

FIGURE 1 is a pure diagram of four connector units and four unitary sets of instrumentalities associated with each other according to the invention;

2

FIGURE 2 is a fragmentary perspective of the end portions of three of the connector units of FIGURE 1;

FIGURE 3 is a transverse section through two of the connector units; and

FIGURE 4 is a fragmentary plan view of one unit connector indicating a different longitudinal spacing for the sets of homologous conductors.

In the embodiment selected to illustrate the invention, four unitary sets of electrical elements or sets of elements are indicated at 10, 12, 14, and 16. It will be obvious that there is no definite limit to the number of such units that may be associated according to the invention. From each unit a composite cable 20, 22, 24, 26 extends from the homologous unitary assembly to one of the supports 30, 32, 34, and 36.

As indicated in FIGURE 2 the supports are laid in overlapping relation like shingles. At one edge each support is provided with means for receiving and engaging the opposite edge of an adjacent duplicate support and holding the two in assembled relation, while the other edge of the first mentioned support is adapted to be received by the female edge of the next support. Thus, as indicated in FIGURE 2 all the supports are arranged one above the other, with a straddling relation between each support and the support below it in the orientation shown in FIGURE 2. For convenience in identification the supports will be mentioned as being above or below each other in the orientation of FIGURE 2, but it is emphasized that they could all lie in substantially the same horizontal plane or they could all have their longitudinal dimension vertical. In fact there is no geometrical orientation that could be assumed that would not be entirely compatible with the functioning of the four supports in combination with each other. It is only necessary that the cables 20, 22, 24, and 26 be long enough to reach from the unitary sets 10, 12, 14, and 16 to the corresponding terminal panels. Therefore, the assembled set of panels and the different sets of electrical elements can all be housed wherever space conditions dictate. This is an advantage in many environments. For instance, within the console of an electronic organ there are often a multitude of sets of electrical elements and storage space is at a premium.

As most conveniently illustrated in FIGURE 3, each set of homologous conductor elements associated with the panel 34 comprises a first conductor 38 in the nature of an extremely thin strip of copper affixed to the face of the panel by the conventional process commonly called "printing." Each such conductor has a proximate end 38-2 and a remote end 38-4 and at least that portion of the conductor extending from the proximate edge 38-2 of the panel 34 up to the point 38-6 carries an extremely thin coating of gold electroplated in place.

A multiplicity of slots 40 are provided in the panel 34, each one extending through the center of its homologous first conductor 38 and through the panel to the other side. From the bight 42-2 the proximate portion of the conductor 42 extends first through the slot 40 at 42-4 and then along the surface of the panel away from the slot at 42-6 where it has electrical contact with the first conductor 38; then outward away from the panel as indicated at 42-8 and continued beyond the portion 42-8 in a short tip 42-10 bent diagonally outward and away from the central portion of the structure. The remote portion of the conductor 42 has the reach 42-12 corresponding to the reach 42-4 and a reach 42-14 corresponding to the reach 42-6 and in electrical contact with the first conductor 38. Beyond that the second conductor is curved gently upward at 42-16 and then around and down with a larger radius of curvature at 42-18 to come back substantially into contact with the panel 34 at 42-20, where

it is bent sharply back away from the panel 34 at 42-22.

The elbow-like tip at 42-22 defines a V-shaped slot adapted to guide the proximate edge of a duplicate panel entered between the tip and the panel 34. In the drawing this is indicated near the bottom of FIGURE 3 where the proximate edge of panel 34 has pushed up the tip 42-22 carried by the panel 30 and the edge of the panel 30 has slid in until it comes into contact with the second conductor of the panel 30 below at the point indicated at 44. Since there are a multiplicity of such second conductors spaced along the length of the panel, it will be obvious that the contacts at 44 afford a precise guide and abutment for ending the insertion of the upper panel. Pushing the upper panel against these contacts 44 secures substantially perfect alignment between the adjacent panels.

Means are provided for securing permanent electrical union of minimum contact resistance between the first and second conductors. I have illustrated an investment of solder which overlies all of the first conductor 38 beneath portions 42-6 and 42-14 of the second conductor and also envelops the second conductor. This solder 46 also extends up as a complete envelope at 48 enclosing reaches 42-8 and 42-10 constituting the proximate end of the second conductor.

This solder is applied by laying masking tape over that portion of the conductor 38 that extends from the conductor 42 over to the proximate edge of the panel with masking tape. The length of the coverage is indicated in FIGURE 3 by the bracket 50. Then the panel 34 is held by its upper edge as viewed in FIGURE 3 and plunged quickly into a solder bath down to the level of the dotted line 52 which crosses the upper edge of the solder investment. This is done before the cable 20 and its insulating support and sheath 54 are assembled with the panel.

The panel is now an integral permanently assembled unit with all its conductors 38 and 42 and the sheath 54 is laid in place and riveted to the panel through suitably positioned holes 56 arranged as in FIGURE 2 or duplicate holes 58 arranged as in FIGURE 4.

Then the cable 20 is assembled in the position illustrated in FIGURE 3 by a series of individual assembly operations, one for each of the conductors 60 making up the cable. The base 54-2 of the sheath 54 is flat and I provide a low side wall at 54-6 and a high side wall at 54-8 leaving an opening for convenient placement of the parts of the cable. The high side wall 54-8 is turned inward again at 54-10 and is slotted by a plurality of narrow kerfs extending down to the dotted line at 64. It will be obvious that a simple gang saw can cut all these kerfs quickly and simultaneously in a single operation.

The individual conductors 60 are of a diameter about $\frac{1}{3}$ or $\frac{1}{4}$ as great as the diameter of conductor 42, and the end of each conductor 60 is wound around its homologous conductor tip 42-10 as indicated in FIGURE 3, by a threading tool such as that illustrated in FIGURE 13 of my Patent 3,027,418, issued Mar. 27, 1962. Each individual conductor 60 is a metallic core enveloped in a sheath of almost microscopic thickness of the order of magnitude of two or three ten-thousandths of an inch, but of adequate insulating power to take care of the potentials involved. This insulating sheath is of special plastic material and per se constitutes no part of my invention, being well known in the art. After the conductor end is wound on the tip 42-10 as indicated in FIGURE 3 the entire assembly is positioned with the tip 42-10 projecting almost vertically downward and immersed in a solder bath down to the dash line 64 (see FIGURE 3). This burns off the insulation of the portion of the conductor wrapped around the tip and I have indicated in dotted lines at 70 the approximate configuration of the resulting tiny gob of solder.

The mechanical loads on the tip 42-10 during the process of assembly are rather heavy for an object of small size and means are provided for reinforcing the

reach 42-8 to assist conductor 42 in resisting such forces. I have illustrated a flange 72 projecting forward from the high wall 54 in a position where the same kerf cut in the high wall and its top flange 54-10 will also penetrate the entirety of the flange 72 and adapt it to receive the reach 42-8 and its envelope of solder in fairly snug engagement in the kerf. This effectively prevents the working forces necessary for assembling the connection at the tip 42-10 from twisting conductor 42 around an axis through its reaches 42-6 and 42-14 and rupturing its contact with its solder investment.

This completes the assembly of the entire panel 34 with the entirety of its associated cable 20. As a rule all the conductors of cable 20 are connected at their other ends with the multiple assembly 10 of electric units before the individual conductors 60 have their remaining ends assembled with the panel 34, but it will be obvious that either the assembly 10 or the panel 34 could be assembled with the cable first, and the other unit last. A third procedure is to position unit 14 and panel 34 the right distance apart on a workbench and affix the conductors 60 at both ends, one at a time.

The assembly of the panel 34 and its first and second conductors, is designed so that it lends itself readily to substantially complete assembly by automatic machinery. For instance, a panel 38 of any desired length can first be cut and stamped and perforated with the desired slots 40 and rivet holes 56. Then it can be mounted on a carriage and moved longitudinally through equal increments equal to the spacing between successive first conductors 38. The second conductors can be fed from a magazine. At each arrest of the longitudinal movement a detector feeler can come up below the panel and if it finds one of the slots it will complete an electric circuit and a plunger from above will push one second conductor down into the assembled position.

The next step is to mask the proximate ends of the first conductors 38 and immerse the assembly in solder up to the remote ends of the reaches 42-14 as indicated by the dotted line 52.

All the subsequent assembly has been previously described.

It will be obvious that the longitudinal spacing of the sets of homologous conductors can be varied to conform to a wide variety of uses. In FIGURE 2 I have indicated groups of twelve sets each assembled with a predetermined minimum longitudinal spacing, with each group of twelve separated from the next group by a much wider spacing at 74. This is an obvious mechanical convenience in designing and assembling electronic organs in which each group of 12 sets of homologous conductors functions to connect one homologous element in one of the units 10, 12, 14, and 16 with the continuous unitary electrical conductor extending, like a bus, through all the homologous first conductors 38 of all the panels, regardless of the number of panels.

In FIGURE 4 I have indicated a design which may still be according to FIGURE 3 but the axial spacing between successive conductors 38 is materially larger and the rivet holes 58 may be somewhat smaller so that the entire panel has only one spacing and may have no gaps at all from end to end of the panel. This provides for a little added convenience in readjusting various experimental assemblies of computers or complicated control arrangements. Referring to the type of association diagrammed in FIGURE 1, the assembly 12 might contain a hundred individual elements and a hundred conductors in its cable 22 while the assembly 10 contained only 85 and a variety of interrelationships could easily be secured for operations of altered programming by separating the panels and moving the panel for assembly 10 up or down a few spaces to connect each of its units to a different element in assembly 12.

Others may readily adapt the invention for use under various conditions of service by employing one or more

of the novel features disclosed, or equivalents thereof. As at present advised, with respect to the apparent scope of my invention, I desire to claim the following subject matter:

1. A multiple connector assembly comprising, in combination: a panel having at least one face of insulating material; a multiplicity of first conductors, each affixed to the insulating face of said panel, and having one end adjacent a first panel edge; a multiplicity of second conductors affixed to said panel; each second conductor having an intermediate portion in electrically conductive contact with the homologous first conductor remote from said first panel edge; each second conductor having two end portions extending away from its contact with its homologous first conductor; one, first, end portion of each second conductor nearest said first panel edge extending out away from said panel and away from said first conductor and ending in a tip remote from said first panel edge and from said first conductor; said tip in a position accessible for the convenient affixing of a third conductor to it; the other, second, end portion of each second conductor extending away from the homologous first conductor in a direction away from said adjacent panel edge; said second end portion being resilient and having a clamping tip remote from said adjacent panel edge and close to the face of said panel; said clamping tip positioned to register with the homologous first conductor of another similar panel, and press against said homologous first conductor to maintain electrical contact therewith and to clamp the first panel edge of said other similar panel against said first-mentioned panel; whereby an indefinite number of similar panels can be removably assembled with each first conductor electrically connected through said second conductor with the homologous first conductor of the other panel; the first and second conductors of said panels constituting a bus with as many lateral taps as there are panels and with the same effective electrical relationship regardless of the sequence in which said panels are juxtaposed.

2. An assembly according to claim 1 in which said first conductors are flat and printed on the face of said panel.

3. An assembly according to claim 1 in which said second conductors are of wire.

4. An assembly according to claim 1 in which said panel has a plurality of apertures, one for each first conductor, each aperture adjacent a portion of its first conductor remote from said first panel edge.

5. An assembly according to claim 4 in which each second conductor has a fastening portion shaped to enter the homologous aperture during assembly and adapted to hold the entire second conductor in assembled position.

6. An assembly according to claim 5 in combination with a solder investment, enveloping said fastening portion and the adjacent portion of said first conductor.

7. An assembly according to claim 6 in which said investment substantially envelops the first end portion and the intermediate portion of said second conductor.

8. An assembly according to claim 1, in combination with an insulating housing of channel cross-section extending parallel to said first panel edge; a multiplicity of insulated third conductors lying in said channel; said channel lying between the end portions of said second conductors and having one, first, leg rising close beside the adjacent first end portions of said second conductors; said channel having a web affixed directly to said panel; said insulated third conductors in said channel having terminal portions each extending up said first channel leg and then outwardly to wrap around the tip of the first end portion of the homologous second conductor.

9. An assembly according to claim 8, in which the tip of the first end portion of each second conductor, and the end of the homologous third conductor wrapped around it, are both enveloped in a single local investment of solder.

10. An assembly according to claim 8 in which the upper edge of said first channel leg has a kerf registering with each second conductor, and said insulated conductors are laid into said kerfs.

11. An assembly according to claim 10 in which the upper edge of said first channel leg is turned in at the top; said kerfs extending across said turned-in top.

12. An assembly according to claim 8 in which said first channel leg has an external rib and said rib has kerfs receiving the homologous first end portions of said second conductors.

13. An assembly according to claim 10 in which said first channel leg has an external rib and said rib has kerfs receiving the homologous first end portions of said second conductors.

14. An assembly according to claim 8 in combination with anchor means mechanically fastening said channel to said panel.

15. An assembly according to claim 8 in which the second leg of said channel extends along adjacent the second end portions of all said second conductors.

16. An assembly according to claim 15 in which said second channel leg is materially narrower than said first leg, and leaves a wide diagonal opening between itself and said first channel leg.

17. An assembly according to claim 8 in which each third, insulated conductor extends from its connection with its homologous second conductor, transversely into said channel and then longitudinally to one end of said channel and out of said channel end.

18. An assembly according to claim 17 in which all said insulated conductors extend out of the same end of said channel.
